OIL IMMERSED FUSE

Filed Nov. 5, 1925

UNITED STATES PATENT OFFICE

FRIEDRICH NATALIS, OF BERLIN-CHARLOTTENBURG, GERMANY, ASSIGNOR TO WESTINGHOUSE ELECTRIC AND MANUFACTURING COMPANY, A CORPORATION OF PENNSYLVANIA

OIL IMMERSED FUSE

Application filed November 5, 1925, Serial No. 67,013, and in Germany January 23, 1925.

My invention relates to electric fuses or cutouts adapted to interrupt an electric circuit upon the passage therethrough of abnormal and dangerous currents, and it has 5 particular relation to oil-immersed fuses for high-tension currents.

It is an object of the present invention to provide a fuse or cutout whereby the arc incident to the rupture of the fuse is quickly 10 extinguished and the circuit interrupted.

Another object of the invention is to provide an oil immersed fuse wherein the oil surrounding the fuse is violently agitated and directed toward the arc upon the rupture of 15 the fuse.

A fuse constructed in accordance with my invention comprises a cylinder of insulating material closed at the ends and having large 20 openings at the sides and fitted with a relatively light movable piston which is connected to a terminal block at one end of the cylinder by a flexible conductor and to a terminal block at the other end of the cylinder by a fusible link. The piston is moved rapidly 25 by the pressure of gas generated by the melting of the fuse, and the arc is extinguished by the inrush of quenching liquid.

In the accompanying drawings:

Figure 1 is a longitudinal sectional view of 30 a fuse embodying features of the invention.

Fig. 2 is a reduced sectional view of an oil filled casing enclosing the fuse structure shown in Figure 1.

An insulating casing 11 is provided with 35 two lateral openings 12 and 13 and comprises an arc-extinguishing chamber 15 having a fusible wire 16 located therein. The chamber is closed at the top by a cover 14, in which is located the detachable terminal member 17 to which is secured a secondary terminal member 18 for the fuse wire 16. The member 17 is secured to the cover 14 by the screw 19, which may also serve to secure the outside conductor to the device. The lower end of 40 the fuse wire 16 is connected, by means of a terminal member 20, to a link 21 and this latter is connected to the terminal 23 by means of a flexible conductor 22.

The link 21 is carried by a cup-like piston 45 24 that is provided with openings 29 in its

bottom and sides, respectively, the purpose of which will hereinafter appear. A tubular member 26, located within the member 11, serves as a stop for the piston 24.

A metal re-inforcing casing 27 surrounds 55 the casing 11 in order to prevent bursting thereof, and a packing ring 28 is provided at the joint between the cover 14 and the casing 11. The piston is made very light so that it will move quickly when the fuse blows and 60 prevent the side wall from being forced out, and so that its movement will be damped by the oil to prevent damage when it strikes the member 26.

The fuse structure above described is designed to be submerged in oil or other insulating liquid 30 contained in a tank 31, and, consequently, the fuse wire 16 and piston or plunger 24 are completely surrounded by insulating fluid. 70

In the event of the passage of current greater than the rated capacity of the fusible element, the pressure generated by the arc resulting from the rupture of the fuse will move the piston rapidly and thus quickly increase the distance between the free ends of the fuse wire. 75

The large openings in the casing and in the piston allow the oil to flow in and quench the arc formed by the melting of the fuse. 80

Oil also is permitted to flow inwardly through the openings 29 in the side of piston and across the arc, thereby causing it to be rapidly cooled and extinguished. The rapid movement of the piston past the openings 12 and 13 in the casing results in violent agitation of the oil and causes cool oil to flow into the space occupied by the arc. 85

In order to replace the fuse wire 16, the casing is first removed from the tank and the terminal member 17 disengaged from the casing. A new fuse element may then be inserted between the member 17 and the link 21. The openings 29 in the sides of the piston 24 permit access to the fastening bolt or screw. 90

The term "electric fuse" in the following claims means an electric conductor of such dimensions and other physical characteristics 100

as to be heated to its melting point by current slightly in excess of the normal full-load current of apparatus connected in series with it, and used for the purpose of protecting such apparatus. This use of the aforesaid term is its usual and well-known significance in the electric art.

It will be apparent from the foregoing description that the fuse device is simple and inexpensive in construction and that the parts thereof are readily accessible for inspection, repair or replacement.

While I have described and illustrated a particular form of the invention, it will be apparent to those skilled in the art that various modifications, addition and omissions may be made therein without departing from the spirit and scope thereof, as set forth in the appended claims.

20 I claim as my invention:

1. In an electric fuse, the combination of a receptacle adapted to contain insulating liquid, a tubular member made of insulating material and disposed within said receptacle, said tubular member having large openings providing communication between the interior of the tubular member and the liquid-containing portion of the receptacle, a closure for said tubular member spaced from the openings, said tubular member forming a chamber between the closure and said openings, a piston disposed within said tubular member, a fusible element disposed within the chamber and normally supporting the piston at the end of said chamber adjacent said openings, said fusible element being fusible by the passage of an excess electric current therethrough, whereby, upon melting of said fusible element, the pressure of the gas generated thereby will propel the piston away from said chamber to permit the insulating liquid to enter through said openings into said chamber to extinguish the arc.

2. In an electric fuse, the combination with an insulating casing closed at the ends and having substantially one half of its central portion cut away, forming a large opening in its sides, of a fusible element and a piston therein located at one end of the opening, the said piston being actuated to the other side of the opening by the pressure developed upon the rupturing of the fusible element.

3. In an electric fuse, the combination with an insulating casing having its central portion cut away leaving large openings in its sides, of a fusible element on one side of the openings, and a hollow piston that is movable past the opened central portion of the casing when propelled by the pressure of the gases developed upon the rupturing of the fusible element.

4. In an electric fuse, the combination with an insulating casing having its upper end closed to form a pressure chamber, the por-

tion therebelow being cut away leaving large openings on its sides the uncut portions of said casing between said openings serving as guide members, of a fusible element within the said pressure chamber and a piston in the lower portion of the said chamber supported by the fusible element and designed to move along the guide members upon the rupturing of the fusible element propelled by the force of the resulting gas in the pressure chamber.

In testimony whereof, I have hereunto subscribed my name this 12th day of October 1925.

FRIEDRICH NATALIS.
